UNITED STATES PATENT OFFICE

ELMER L. ENNIS, OF GARY, INDIANA

EXCAVATING MACHINE

Application filed June 8, 1931. Serial No. 542,930.

My present invention relates to improvements in excavating machines of the sub-grade type, which while adapted for various purposes, are especially designed for use in the construction and grading of roadbeds, highways, etc. preparatory to laying of the macadam, concrete, or other similar material.

The machine is equipped with rollers or wheels adapted to run on the spaced, parallel, forms at the lateral edges of the roadbed, which provide rails upon which the machine may roll and a motor is mounted on the machine to provide power for propulsion of the machine as well as for operating or driving the conveyers. Means are also provided whereby the machine may be pulled, as by a tractor, for accomplishing grading operations, and an auxiliary draft rigging may be provided, for use in transporting the machine from place to place, or from one section of the road under construction to another section.

In carrying out my invention I utilize a scraper that is vertically adjustable relative to the roadbed, or rather, the machine carrying the rigidly mounted scraper, is adjustable relatively to the forms upon which the machine rolls, and the scraper blade is adjustable for crowning the roadbed, regardless of whether the surface of the roadbed is level, or is tilted to one side as in rounding curves in the roadway.

For leveling and filling the roadway, the scraper blade is employed and the motor is operated to drive the machine back and forth on its forms or rails to make cuts and fills, and conveyers are utilized for distributing excess material collected or gathered by the scraper.

The invention consists in certain novel combinations and arrangements of parts as will hereinafter be more fully set forth and claimed. In the accompanying drawings I have illustrated one complete example of the physical embodiment of my invention wherein the parts are combined and arranged according to the best mode I have thus far devised for the practical application of the principles of my invention. It will be under-

stood that alterations and changes may be made in the exemplified structure, as for instance, in the driving and transmission mechanisms, and in the adjusting means, and in other parts, within the scope of my claims without departing from the principles of my invention.

It will also be understood that parts, such as flooring or deck portions, shields, and other features of the complete machine have been omitted from the drawings, in order that the operating parts may not be obscured. These, and other parts not illustrated, will form part of the equipment of the machine in operation.

Figure 1 is a view in front elevation of the excavating machine embodying my invention, showing the spaced side-rails or forms in section, and omitting some of the details of construction, in the interest of a ready understanding of the machine.

Figure 2 is a top plan of the machine of Figure 1.

Figure 3 is an enlarged, vertical sectional view of the machine, and Figure 4 is a complementary end view of the machine as seen from the side of the roadway.

Figures 5 and 6 are detailed views enlarged, showing one of a pair of adjusting devices, for vertically adjusting the machine with relation to its supporting front wheels.

Figure 7 is an enlarged detail view at the left front of the machine showing one of the adjustable elevators, and other details, and Figure 8 is a detail showing the joint between the pivoted sections of the elevators.

Figure 9 is a plan view on a reduced scale, illustrating the carriage rigging for the machine, by means of which the machine may be lifted from the forms, and then transported, as desired.

In the preferred form of my invention I utilize a rectangular main frame made up of I-beams 1 and 2, and the special front beam 3, together with channel irons or bars 4, the latter extending longitudinally of the roadway to be graded, and these parts form a rigid main frame, suitably braced, and equipped with floor boards, or a deck as required.

As best seen in Figure 3 the front beam 3

100

is provided with a web having a slope of approximately 40° to the vertical, and the scraper blade 5 is supported in advance of this beam and substantially below the level of the machine frame. The bottom edge of the scraper blade is fashioned to slope outwardly from the center toward its ends to provide a crown in the roadway, and the opposite ends of the blade are turned slightly forward for the purpose of gathering the material, and guiding the material to the rear as the blade advances.

The scraper blade is adjustably mounted on a holder 6 that extends transversely of the roadway in the form an angle iron bar, and this bar is vertically slotted, as at 7, to accommodate the clamping bolts 8 that pass through the scraper blade and the slots and are secured at the rear by the nuts 9 at the back of the holder.

These bolts 8 are provided with eyes 10 at the front of the scraper blade, for the attachment of chains or cables from a tractor, and the latter may be used for hauling or drawing the machine and scraper blade in the preliminary grading of the roadway.

The blade-holder 6 is rigidly bolted or riveted to a flat metal plate 11, and the latter is rigidly bolted or riveted to the lower flange 20 of the beam 3, back of and at the top of the scraper blade, and this plate forms an apron or shelf upon which the soil is pushed or forced by the scraper blade, to be disposed of as will hereinafter be explained. A number 35 of brace bars 12 are located under the apron and bolted at their ends to the lower flange of the beam 3 and to the holder 6 for bracing the blade against the resistance of the soil as the blade advances.

40 The machine is supported on wheels 13 and 14 at the front and 15 and 16 at the rear corners of the rectangular frame, and the wheels as shown are adapted to roll back and forth on the two channel beams 17 and 18 spaced at proper distances and arranged in parallelism at the sides of the roadway.

50 The scraper blade, which is rigid with the main frame, and the front portion of the frame, may be elevated with relation to the forms or tracks 17, 18, in order to adjust the lower edge of the scraper to the desired level of the surface of the graded roadway, and for this purpose the front wheels are provided with bearing plates 19 with relation to which the front portion of the main frame 55 may be raised or lowered.

As best seen in Figure 6 the bearing plate is provided with a trunnion 20 on which the wheel (13 or 14) is journaled, and on the outer face of the channel bar 4 of the frame are secured a pair of spaced, flanged plates 21 overlapping the opposite edges of the bearing plate and forming with the outer face of the channel beam a retaining and guide slot that permits free vertical movement of

the frame with relation to the bearing plates. As the front of the frame and the scraper are raised or lowered they swing on the axles 22 of the rear wheels 15 and 16.

Each wheel, 13 and 14, is provided with a bearing plate 19, and each plate is provided with a manually operated lifting lever 23, fulcrumed at 24 in a bracket on the frame, and pivoted at the end of its short arm, as at 24, to the upper end of the bearing plate. Any suitable means may be employed for retaining the lever in adjusted position, as the pawl 25 pivoted on the lever and adapted to engage a tooth in the segmental rack 26 supported on the top of the main frame. Thus it will be apparent that by swinging the lever to the right in Figure 6, the frame and scraper bar may be lifted or elevated, or by swinging the lever to the left the parts may be lowered, with relation to the stationary bearing plate 19.

80 The machine may be driven forward and backward with power supplied from a suitable motor, indicated in a conventional manner at 27, the motor being shown as mounted on the upper or top portion of the main frame. From the motor shaft 28, a chain drive 29 extends to and drives the power shaft 30 that is journaled in bearings and is disposed transversely of the machine in front of the motor. A drive shaft 31 is journaled in bearings in the main frame, and driven from the power shaft by means of the bevel gear couples 32 and 33 and gear shaft 34, and the drive shaft has at its ends sprocket wheels 35 that engage the sprocket chains 36 which pass around the sprocket wheels 37 mounted on the four wheels 13, 14, 15, and 16. The gear couple 32 comprises slideable bevel gears adapted to be shifted into and out of mesh, alternately, with a similar gear on the power shaft 30, and by shifting these gears it will be apparent that the gear shaft 34 may be revolved in opposite directions thereby transmitting the power in alternately opposite directions to the drive shaft 31 for advancing and rearwardly moving the machine. The gear couple 32 and other similar gear couples of the machine are of course under manual control, and the gears are shifted at will for accomplishing the reverse movements of the operating parts.

85 As the machine is run forward and backward to operate the scraper for leveling, cutting, and filling, the surface of the roadway, the scraper is guided and braced laterally by means of guide rollers 38, mounted on vertical journals, and carried at the opposite ends of the scraper blade, in position to roll along the inner faces of the two forms of channel bars forming the rails 17, and 18 for the wheels of the machine.

90 As the scraper advances, excess material is lifted on top of the apron 11, and if desired this material may be conveyed and

dumped at either side of the roadway, or simultaneously at both sides of the roadway, beyond the forms 17 and 18.

For conveying the material I employ two sets of endless conveyers 39 and 40, and 41 and 42, the latter being adjustable elevators at opposite ends of the machine designed to elevate the material and dump the material at the sides of the roadway beyond the forms 17 and 18.

All of the endless conveyers include suitable endless belts provided with the customary conveyer blades indicated as 43 and spaced at suitable intervals apart for conveying the material.

The two conveyers 39 and 40 traverse the space in the front of the beam 3 and are located above the rear part of the apron, in order that they may move the material as it is backed up by the scraper blade on the top of the apron. The endless conveyers may move the material in opposite directions towards the sides of the machine, or these conveyers 39 and 40 may move the material in one and the same direction. Conveyer 39 may move the material to the elevator 41 while conveyor 40 is moving material to the elevator 42; both conveyers may move the material to elevator 41; or both conveyers may move the material toward the elevator 42.

The endless belts of the conveyers pass around spaced rollers 43^x and the shafts 44 of the rollers are journaled in adjustable bearings at 45, and similar adjustable bearings are provided for the elevators, for use as belt tighteners for the endless belts and chains of the conveyers and elevators.

The rollers 43^x are provided with one or more sprocket wheels 43' and the conveyers have one or more chans 43a at the edges of the belts for co-action with the wheels. The upper ends of the two outermost shafts 44 are provided with gear couples as 46 that are operated by gear shafts 47, and it will be noted that the rollers and the conveyers are disposed at approximately an angle of 40 degrees to the horizontal plane of the machine. The gear shafts 47 receive power from the power shaft 30, through the shiftable gear coupling 48, and it will be apparent that by shifting the gears of the coupling 48 the direction of movement of the endless conveyers may be controlled for moving the excess material transversely of the machine on the apron.

The adjustable, endless elevators 41 and 42 are also driven from the power shaft 30 and they are provided with shiftable gear couplings 49 on the shaft 30 for controlling the operation of the respective elevators.

The inner ends of the elevators project downwardly through openings provided therefor in the opposite ends of the apron 11, and as best seen in Figure 7 the drive

shaft 50 of each elevator is journaled in bearings 50' mounted on and beneath the main frame. This drive shaft is revolved through the gear couple 51 and vertical gear shaft 52, and the latter shaft is journaled in suitable bearings, and equipped at its upper end with a gear 53 for co-action with the clutch gear 49 of the power shaft.

The elevators are actuated through one or more sprocket wheels 54 and chains 54', and the elevators are mounted in frames 55 mounted on the driving shafts 50, which frames are rigidly secured by brackets 55a. In order that the outer ends of the elevators may be vertically adjusted with relation to the main section, for dumping the material over these outer ends, each elevator has an extension frame 55b, pivoted at 55c on the fixed section 55.

For supporting the adjustable extensions in adjusted position, I employ rigid upright posts 56, to which the brackets 55a are bolted, and the posts are secured at the opposite ends of the apron. At the upper ends of these posts are pivoted (as at 57) adjusting arms 58 that are pivoted at 59 to the adjustable extensions 55b of the elevators. The arms 58 are extensible and are equipped with turn buckles 60 for that purpose, and the extension frames may be provided with spaced pins 61 for the pivotal connection of the adjusting arms thereto. A yoke 62 may be employed and disposed transversely of the extension to provide a supporting point, as 59 at opposite sides of the extension frame to insure a stable support for the elevator extension.

In Figure 9 the machine is illustrated with a transportation rig by means of which the machine may be elevated a sufficient height above the ground level to enable trundling of the machine, when drawn by a tractor, and by means of the tractor the machine may be hauled or towed to its desired destination, on the pair of wheels 60a.

The wheels are journaled on the ends of a crank axle 61a and the crank axle is journaled in bearings 62a of the main frame. By means of a set of reduction gears indicated at 63, that connect the axle with the power shaft 64, and the crank arm or crank wheel 65 on the power shaft or crank shaft, the latter may be turned to swing the crank ends of the crank axle down to vertical position, and continued operating of the train of gears will lift the machine above the ground. In this elevated position the machine is free of the ground, and after the gearing 63 has been locked, as at 66, the machine is supported on the pair of wheels 60a and may be hauled or towed as desired.

The crank axle as shown extends at right angles to the axles of the rollers or wheels 13, 14, 15 and 16 of the machine, that is, transversely of the longer axis of the machine, in order that the machine may occupy a minimum road-space while it

is being towed in the direction of its longer or longitudinal axis.

After the machine has been towed or trundled to its destination for grading work, it is arranged in position over the forms 17 and 18, the reduction gears 63 are released, but controlled, and the machine is permitted to sink by gravity to the rails or forms where it is supported on its wheels 13, 14, 15 and 16. The crank axle 61^a is then turned up to position of Figure 7 in order that the transportation rig may be out of the way of the operations of the excavator.

Having thus fully described my invention, what I claim as new and desire to secure by Letters Patent is:

1. In a wheeled excavating machine the combination with a main frame, a front scraper-blade, and a rigid plate joining the frame blade and forming an apron for excess material, of an endless laterally moving conveyer mounted at the rear of and over said apron, an endless elevator at an end of the conveyer in position to receive material therefrom, means for driving the machine, and means for operating the elevator and the conveyer.

2. In a wheeled excavating machine, the combination with a main frame, a front scraper blade, a rigid horizontal apron joining said frame and blade, and means for elevating the front of the frame and the scraper blade, of an endless laterally moving conveyer mounted at the rear of and over said apron, an endless elevator at an end of said conveyer in position to receive material therefrom, means for propelling the machine, and means for operating the elevator and the conveyer.

3. In a wheeled excavating machine, the combination with a main frame, a scraper blade, and an apron rigidly joining said blade and frame, of means for conveying material from the blade laterally across the apron and means for vertically adjusting the scraper end of the main frame with relation to a roadbed.

4. In a wheeled excavating machine, the combination with a main frame, a scraper blade below the frame, and a plate rigidly joining said blade and frame and forming a horizontal apron for excess material, of means for conveying material from the center toward both ends of the apron, and elevating means at both ends of the apron for disposing of said material.

5. In a wheeled excavating machine, the combination with a main frame, a scraper blade below the frame, and a plate rigidly joining the frame and blade and forming a horizontal apron for excess material, of a pair of endless conveyers adapted to convey material from the center toward the ends of the apron, and a pair of endless elevators adapted to receive said material at the outer ends of said conveyers.

6. In a wheeled excavating machine, the combination with a main frame and means for vertically adjusting its front end, a scraper blade, and a plate rigidly joining the front end of the frame and the blade and forming a horizontal apron for excess material, of a pair of endless conveyers adapted to convey from the center toward the ends of the apron, and an endless elevator at the outer end of each conveyer adapted to receive the material from said conveyers.

7. In a wheeled excavating machine, the combination with a main frame and means for vertically adjusting said frame with relation to the front wheels of the vehicle, a scraper blade below and in front of the frame, and a plate rigidly joining the frame and blade and forming a horizontal apron for excess material, of a pair of endless conveyers adapted to convey material from the center toward the ends of the apron, means for reversing the movement of the conveyers, an endless elevator at the outer end of each conveyer, and means for vertically adjusting the outer ends of said elevators.

In testimony whereof I have affixed my signature.

ELMER L. ENNIS.
